UNITED STATES PATENT OFFICE

FREDERICK J. KOEHLER, OF PORTLAND, OREGON.

SOUND INTENSIFIER.

Application filed February 24, 1925. Serial No. 11,192.

To all whom it may concern:

Be it known that I, FREDERICK J. KOEHLER, a citizen of the United States, residing at Portland, in the county of Multnomah and State of Oregon, have invented a new and useful Sound Intensifier, of which the following is a specification.

My invention relates to sound intensifiers in which a membrane is stretched tight over a frame, with a metal cross resting on the membrane; vibrations to the iron cross being transmitted through a hardwood pin.

The objects of my invention are to produce a comparatively simple device which reproduces sounds true to their natural tones yet greatly increased in volume, moreover without the use of any horn.

Other objects and advantages are to be found in the construction and arrangement of parts as will be described in the specification, and particularly pointed out in the appended claims.

I attain these objects with the mechanism illustrated in the accompanying drawing, in which:

Fig. 1 is a plan view of the entire mechanism.

Fig. 2 is a side elevation partly in section.

Over a frame 1 of suitable material is stretched a membrane 2 preferably composed of the skin of a calf or such like animal; to obtain the best results it is important that the skin be stretched as tight as the limits of elasticity will permit. This skin or membrane 2 is glued to a hoop 3, and the edge 4 of said membrane is bent upward for greater security against slipping. A slip ring 5 presses against the hoop 3 and holds the membrane 2 tight. The pins 6 hold the slip ring 5 and frame 1 together. At the center of the membrane 2 and parallel thereto is a vibrating unit composed of a metal cross 7 whose ends are bent toward the membrane 2 and terminate in flat pointed prongs 8. Thin sharp pointed prongs would pierce the membrane too quickly,—the contact surface of the prongs must therefore be proportioned to the strength of the membrane 2. The metal cross 7 is held to the membrane 2 by means of the screws 9, the washers 10 being interposed to prevent the cutting of the membrane 2. Although the screws 9 should be

as close as possible to the prongs 8, the latter should not rest directly on the head of the screws 9, but should still leave a small amount of flexible membrane 2 between the respective edges. A hardwood pin 11 is firmly secured in the center of the metal cross 7 and extends through the membrane 2 for a suitable distance. The aperture 12 in the membrane 2 should be just large enough to prevent interferences between the vibrations of the membrane 2 and the hardwood pin 11 as the main vibrations should be transmitted to the membrane by the prongs 8. Vibrations to the free end of the hardwood pin 11 can now be transmitted by telephone, phonograph, radio, or suchlike means, and the resultant sound will not only be greatly increased in volume, but free from harsh metallic noises, and will reproduce tones in their natural softness.

Having thus described my invention, it will be seen that my objects have been accomplished and, though I have shown the preferred form of construction, I reserve to myself the right to make minor changes providing I do not violate the spirit and principle of my invention.

I claim as a basic patent:

1. In a sound intensifier, the combination of a membrane, with a vibrating unit at the center of the membrane, said vibrating unit comprising a metal cross in a plane parallel to the membrane, the arms of said cross bending toward the membrane and terminating in prongs in close contact with the membrane, and a hardwood pin extending from the center of the metal cross through the membrane.

2. In a sound intensifier, the combination of a membrane, with a vibrating unit, said vibrating unit comprising a metal cross in spaced relation to the membrane and parallel thereto, contact prongs from the ends of the metal cross to the membrane, screws holding the metal cross to the membrane, said screws being located adjacent to the prongs without said prongs actually resting upon the head of the screw, and a hardwood pin extending from the center of the metal cross through the membrane.

3. In a sound intensifier, the combination of a membrane, with a vibrating unit, said vibrating unit comprising a metal cross,

the center of the membrane and parallel thereto, prongs at the ends of the metal cross in contact with the membrane, screws to hold the ends of the metal cross to the membrane, an aperture in the center of the membrane, and a hardwood pin extending from the center of the metal cross through the aperture, said aperture being slightly larger than the diameter of the hardwood pin.

Signed by me at Portland, Oregon, this 11th day of February, 1925.

F. J. KOEHLER.
